UNITED STATES PATENT OFFICE.

WALTER RICHARDSON, OF NEW YORK, N. Y., ASSIGNOR TO HENRY TRENCHARD, JR.,
OF BROOKLYN, NEW YORK.

APPARATUS FOR APPLYING FASTENING DEVICES TO AND FOR ENVELOPS, &c.

1,286,413.

Specification of Letters Patent.

Patented Dec. 3, 1918.

Application filed May 10, 1916. Serial No. 96,693.

To all whom it may concern:

Be it known that I, WALTER RICHARDSON, a citizen of the United States, and a resident of the borough of Manhattan, city, county, and State of New York, have invented certain new and useful Improvements in Apparatus for Applying Fastening Devices to and for Envelops, &c., of which the following is a specification.

10 My improvements relate to means for equipping commercial packages, envelops, and the like, with fastening devices of the class in which a pronged eyelet clasp, on the receptacle part, is used in conjunction with 15 a perforation formed for its reception, on the flap, to secure the latter in closed relationship to said receptacle part in a manner now well known in the art,—the flap perforation being ordinarily reinforced by annular washers or "patches" applied to opposite sides of the flap, and one of said annular reinforcing patches, the one on the outside of the flap, frequently bearing an imprint. These results have heretofore been 25 attained by the use of three separate machines, involving three separate handlings or manipulations, also necessitating transfer from one machine to another, and involving considerable waste of time and effort, to say 30 nothing of the initial cost of three machines, and of the power consumed in running them.

It is the main object of my invention to conserve time, labor, and energy in this respect, while rendering the service more efficient by accomplishing all three functions referred to at a single operation as herein-after set forth, the invention consisting in the specific combination, construction and arrangement of parts described and claimed.— 35 The distinctive feature being the assembling and coördinating in one apparatus of means for simultaneously feeding and securing the pronged eyelet clasp to the envelop, perforating and reinforcing the flap, and imprinting thereon when required.

In the accompanying drawings,

Figure 1, is a front elevation of the apparatus;

Fig. 2, is an end elevation thereof;

50 Fig. 3, is a plan thereof;

Fig. 4, is what may be designated as a front view of the feed hopper, channel, etc., as they are positioned in the machine so that the open face of the feed channel is in full 55 view of the operator;

Fig. 5, is an elevation, partly in section, taken at right angles to Fig. 4;

Fig. 6, is a transverse section taken upon a horizontal plane of the channel standard U looking downward;

Fig. 7, is a perspective view of one of the relief gates provided at the lower end of the feed channel;

Fig. 8, is a perspective view of the feed check lever or gate escapement;

Fig. 9, a view upon a larger scale of the lower part of the feed channel partly broken away and in section to show the operation of the feed check or escapement;

Fig. 10, is a transverse section taken upon 70 plane of line 10—10, Fig. 9;

Fig. 11, is a perspective view of the clip rest at the bottom of the feed channel:

Fig. 12, is a rear or inside view of the rotatable feed hopper, the feed channel being 75 shown in dotted lines;

Fig. 13, is a horizontal sectional elevation taken upon plane of line 13—13, Fig. 4;

Fig. 14, is an elevation on a larger scale of the inner face of the hopper plate, the 80 rotatable hopper being omitted;

Fig. 15, is a perspective view of the hopper return guard;

Fig. 16, is a top view of the feed hopper, etc.;

Fig. 17, is a horizontal section taken upon line 17—17, Fig. 14, but on a smaller scale;

Fig. 18, is a perspective view of the adjustable foot or bracket on which the feed channel standard is supported;

Fig. 19, is a perspective view of the adjustable bearing for the outer end of the rotatable feed hopper shaft;

Fig. 20, is a plan of the operative parts which act directly upon the envelop;

Fig. 21, is a sectional elevation taken upon plane of line 20—20, Fig. 20;

Fig. 22, is a sectional elevation, full size, illustrating the relative positions of the dies, etc., prior to action;

Fig. 23, is a similar view illustrating the action of the patch cutting and applying dies, and also that of the printing die;

Fig. 24, is a horizontal section taken upon plane of line 23—23, Fig. 22;

Fig. 25, is a perspective view of the imprint die block;

Fig. 26, is a perspective view of the anti-friction printing platen plate;

Fig. 27, is a view of a portion of an en-

velop flap showing an imprint on the outer reinforcing patch;

Fig. 28, is a sectional elevation similar to Figs. 22, and 23, illustrating the action of the perforating and wad-ejecting punch;

Figs. 29, and 30, are sectional elevations illustrating in detail the clip applying mechanism and the operation thereof;

Fig. 31, is a perspective view of a two prong clip fastening before application to the body portion of an envelop;

Fig. 32, is a sectional view of a portion of an envelop body and clip applied thereto;

Fig. 33, is a sectional view of an envelop flap formed with a prong-receiving opening reinforced by patches;

Fig. 34, is a view of a portion of the right hand or outside patch strip after being subjected to the action of the patch dies and printing die and the ejector punch;

Fig. 35, is an elevation of the envelop feed gage table and its adjustable supports, showing an envelop in position thereon, and showing by dotted lines the table in an inclined position;

Fig. 36, is a horizontal section and plan on a smaller scale taken upon plane of line 36—36, Fig. 35;

Fig. 37, is a perspective view of the envelop gage, detached;

Fig. 38, is an elevation of the reinforcing patch strip feed mechanism, taken on the left side thereof;

Fig. 39, is a front elevation thereof;

Fig. 40, is a sectional detail on a larger scale taken upon plane of line 40—40, Fig. 38;

Fig. 41, is a horizontal section taken upon plane of line 41—41, Fig. 38;

Fig. 42, is an isometrical view of one of the patch strip feed guards;

Fig. 43, is an isometrical view of one of the scrapers used on the feed rollers as shown in Figs. 39, and 40;

Fig. 44, is an enlarged detail of the feed rolls, ratchet, and hand lever;

Fig. 45, is an elevation, partly in section, of the power clutch mechanism;

Fig. 46, is a transverse section upon plane of line 46—46, Fig. 45;

Fig. 47, is a detail view of the cam portion of the clutch sleeve;

Fig. 48, is a detail view of the inner or free end of the feed cam lever;

Fig. 49, is a sectional detail upon a larger scale than Fig. 48, of certain parts of the eyelet-riveting punch;

Fig. 50, is a sectional detail taken upon plane of line 50—50, Fig. 29, showing means for effecting the lateral horizontal adjustment of the eyelet-riveting patch;

Fig. 51, is a perspective view of the open end of an envelop after treatment by my apparatus;

Fig. 52, is a view like unto Fig. 9, on the

same sheet of drawings, showing the reverse position of the clip escapement and the release doors open, the latter having been omitted from Fig. 9, except as indicated therein in dotted lines.

In the drawings *a*, *a*, represent the basic frame or table of the machine supported on legs *a'*, *a'*. Looking from the front of the apparatus, as in Fig. 1, the cam shaft *C*, may be said to extend transversely across the table *a*, being mounted in bearings *a²*, *a³*, and being held against longitudinal movement by the cams *C'*, *C³*, which abut against the inner sides of said bearings *a²*, *a³*, and act, in this respect, as retaining collars on the cam shaft *C*, for the purpose designated.

Upon the right extremity of the cam shaft *C*, is loosely mounted a power pulley *P*, the hub of which is formed with an annular groove *p*, within which rests a detent *c*, mounted upon a collar *c'*, rigidly secured on the end of the shaft *C*. Thus the detent *c*, allows the power pulley *P*, to rotate freely on the shaft *C*, while holding it against longitudinal movement thereon.

Splined to the shaft *C*, as shown in Fig. 46, so as to be slidable thereon longitudinally between the right hand bearing *a³*, and the power pulley *P*, is the clutch sleeve *c⁴*, formed with jaw teeth *c⁵*, for engagement with corresponding jaw teeth *p'*, on the left hand side of the hub of the power pulley *P*. In Fig. 45, to which reference may be had for a clear understanding of the power clutch mechanism, the jaw teeth *c⁵*, and *p'*, are shown in solid lines as out of engagement because the clutch sleeve *c⁴*, is retracted against the resistance of the compressible spring *c⁶*, which is seated in a recess formed for its reception in the lower part of the journal bearing *a³*, and which tends constantly, by its action on the plunger *c⁷*, to thrust the clutch sleeve *c⁴*, into engagement with the hub of the power pulley *P*, to thereby rotate the cam shaft *C*. The clutch sleeve *c⁴*, is held in its retracted position by a spring latch or bolt *b*, which engages normally with an annular shoulder *c⁴¹*, on the clutch sleeve *c⁴*, but which, when withdrawn by the depression of the foot pedal or treadle *B*, acting through the medium of the connecting rod *b'*, and rock lever *b²*, (against the resistance of the retractile spring *b³*, see Fig. 2) on which the bolt *b*, is mounted, releases the clutch sleeve to the impulse of the compression spring *c⁶*.

When the foot pedal *B*, is released the spring *b³*, returns the treadle and connections to normal position with the bolt *b*, (which may be in the form of a roller) again protruding into the path of the cam portion *c⁴²*, of the clutch sleeve shoulder *c⁴¹*, so that by its continued rotation with the shaft *C*, the cam sleeve *c⁴* will force itself out of engagement with the hub of the power pulley *P*, thereby releasing the

cam shaft C, until the treadle is again depressed to release the clutch sleeve and effect another cycle of operation,—it being understood of course, that the apparatus is 5 practically at rest while a finished envelop is being removed and another substituted, and that the treadle B, is depressed only when a new envelop is in position for treatment. When at rest in normal position the 10 bolt b, contacts with a shoulder c⁴⁸, adjacent to the apex of the cam portion c⁴², of the clutch sleeve c⁴, as shown in Fig. 47.

The left end of the cam shaft C, is provided with a hand wheel c⁸, to facilitate the 15 turning and manipulation of the shaft and cams for any reason when the clutch sleeve c⁴, is not in engagement with the hub of the power pulley P, as for the purposes of inspection, cleaning dies, etc. In such case 20 the clutch sleeve c⁴, is positively held out of engagement with the hub of the power pulley by a cotter pin c⁹, inserted through a hole c¹⁰ drilled in the clutch sleeve c⁴, and into engagement with a hole c¹¹, in the cam 25 shaft C, as shown in Fig. 46, or by any other mechanical expedient.

The hand wheel c⁸, is made of such weight and proportion as also to act as a fly wheel to steady and complete the rotation of the 30 cam shaft.

The combined function of the apparatus, as heretofore intimated, is, at one cycle of operation, to punch a clip prong receiving hole in an envelop flap and apply thereto 35 around said hole an "inner" reinforcing "patch" to the inner side of the flap and an "outer" reinforcing patch to the outer side of the flap while making an imprint on the patch strip for the next succeeding outer 40 patch, and while "riveting" and securing an eyelet clip to the body portion of the envelop in position for subsequent engagement with the reinforced clip hole.

The cams C', C², C³, are rigidly attached 45 to the shaft C. Cam C', actuates, through the medium of the cam lever D', the inner patch die I, and the clip eyelet "rivet" punch R; the cam C², actuates through the medium of the cam lever D², the outer patch die K, 50 and the imprint or type die N'; while the cam C³, actuates, through the medium of the cam lever D³, the ejector punch E, which punches the central clip hole through 55 both reinforcing patches and through the envelop flap after they are applied thereto, and then effects the ejection of this central waste through the inner patch die I, as hereinafter more fully set forth. The cam levers D', D², D³, are of the second order, 60 being fulcrumed to the table a, at their rear extremities, as at d', d², d³, the power being applied to their medially positioned cam pins which protrude into the respective grooves of the cams C', C², C³, and being 65 transmitted by the outer or front ends of

said cam levers, as above intimated, to the patch dies I, K, printing plunger N', and punches R, E.

A fourth cam C⁴, also rigidly attached to the cam shaft C, is the patch strip feed 70 cam which actuates the mechanism by which the patch strips s', s², are drawn through the apparatus. The patch strips s', s², as ordinarily used consist of ribbons of paper s', s², one side of each of which is coated 75 with an adhesive which is moistened prior to the feeding of the strips to the patch dies I, K, E, and on opposite sides of an envelop flap f, inserted between them, the action of the dies severing a reinforcing ring s'', s²², 80 from each strip s', s², and applying them to the envelop flap f, with the result shown in Fig. 33. Thus, as shown in the drawings, spools of patch ribbon paper s', s², are mounted on spindles a⁴, a², projecting from 85 a cross bar a⁵, attached to the front legs of the machine, and from these spools a⁴, the patch ribbons or strips s', s², are fed to and over idler rollers g, g, which moisten the adhesive on the inner side of each strip, the 90 moistening rollers being partially immersed in water (as shown on the right of Fig. 21) contained in pans or holders g², g², suspended from the bed a, of the apparatus upon brackets a⁶, a⁶, g', g', are covers to protect the receptacles g², g², from extraneous matter. It is obvious that if ungummed strips s', s², are used, the adhesive may be applied by the idler rollers g, g,—a liquid 95 adhesive being substituted for the water. 100

From the moistening rollers g, g, the paper strips s', s², pass up through slots a', a¹, in the bearings i², e, as shown in Figs. 21, to 24, inclusive, to the tension forwarding rolls d⁴, d⁵, which pull the patch 105 strips s', s², through the apparatus, discharging the waste from which the reinforcing patches s'', s²², have been punched,—the strips s', s², converging as they pass to and between said tension forwarding rolls d⁴, d⁵, (as shown in Figs 39 and 40) from which they pass out through the guards d²¹, d²¹, which prevent the waste s*, from following and winding around the peripheries of said forwarding rolls d⁴, d⁵. 110 The strip s', passes through a guide a⁸ which prevents it from contacting with the other strip s², until they converge to the rollers d⁴, d⁵, as above stated. 115

The shafts of the forwarding rollers d⁴, d⁵, 120 are mounted in a rectangular frame a⁹, forming the upper portion of the standard a¹⁰, rigidly secured to the base or table a, to which standard a¹⁰, the strip guide a⁸, above referred to is also rigidly attached. The 125 journals of the lower roll d⁵, have fixed bearings, but the journals of the upper roll d⁴, rest in vertical slots a'', in the side members of the frame a⁹, (as shown in the case of one in Figs. 1, and 40) and are held down by 130

elastic resilient pressure so as to tend constantly to maintain peripheral contact between the rolls d^4 , d^5 , while allowing the upper roll d^4 , to accommodate itself to the combined thickness of the patch strips s' , s^2 , when inserted between said forwarding rolls. The lower roll d^5 , is intermittently rotated positively at each revolution of the cam shaft C, a peripheral space equivalent to the 10 distance between the centers of adjoining circular openings s , formed in the strips s' , s^2 , by the removal of the reinforcing patches s' , s^{22} , so that the feed is uniform and automatic. This automatic intermittent rotation 15 of the forwarding rolls d^4 , d^5 , is effected by means of a ratchet wheel d^6 , actuated by a pawl d^7 ,—the two rolls d^4 , d^5 , being made to rotate in unison by intermeshing gears d'' , d^{22} , attached to their respective shafts as will 20 be seen more particularly by reference to Fig. 38. The pawl d^7 , is attached at its lower extremity to the inner free end of a cam lever D^4 , which is pivotally supported at its other end upon a bifurcated standard 25 a^{12} , on the frame bed a , as seen more particularly in Figs. 2, 3, and 38. The cam C⁴, is of the peripheral type, having the eccentric portion c^{44} , by which the cam lever D^4 , is raised, and the depression c^{45} , with which 30 the free end of the detent D⁵, engages as shown in Fig. 38, when the parts are at rest,—said detent D⁵, being pivotally supported on the bifurcated standard a^{12} , and having a compression spring d^8 , interposed 35 between its outer end and the table a . The function of the detent D⁵, is to prevent back rotation of the cam shaft C, under all circumstances.

The ratchet wheel d^6 , may be also actuated 40 independently of the pawl d^7 , by a small hand lever d^{44} , fulcrumed on the shaft of the roll d^5 , and provided with a spring pawl d^{45} , (see more particularly Fig. 44) which, when said lever d^{44} , is depressed, pulls over said 45 ratchet wheel d^6 , rotating the rolls d^5 , d^4 , sufficiently to facilitate the introduction by hand of the waste strips s^x , between the rolls as a preliminary to starting the machine; or the hand pawl lever d^{44} , may be utilized for 50 the purpose of advancing the feed of patch strips s' , s^2 , if rendered desirable for any reason during the use of the apparatus. Each roll d^4 , d^5 , is provided with a scraper d^x , by which it is kept free of gum, fiber, etc., 55 that would otherwise collect thereon.

During the ordinary operation of the machine the cam C⁴, in rotating raises the cam lever D^4 , sufficiently to cause the pawl d^7 , to advance the ribbons s' , s^2 , one space as hereinbefore set forth. That is to say the thrust 60 of the cam C⁴, is equivalent to the distance between the centers of the reinforcing washers s'' , s^{22} , as severed from the strips s' , s^2 . The pawl d^7 , is hinged or articulately attached to the cam lever D^4 , by any mechani-

cal expedient, as by passing a tongue d^{51} , through a slot in the said lever and securing same by a cotter pin, as shown in Fig. 48, or otherwise. Said pawl d^7 , is held in contact with the ratchet wheel d^6 , by spring d^{61} , at 70 tached to the lever D^4 .

The bifurcated forward end of the cam lever D⁴, straddles the hollow patch die tube I, which is mounted slidably in the bearings i' , and i^2 , both of which, in the construction 75 shown in the drawings, form part of the table bracket i, as will be seen more particularly by reference to Fig. 21, said bracket i, being secured to rigid extensions a^{21} , and a^{22} , of the table or base a. The said forward end 80 of the cam lever D⁴, rests between a collar i^3 , and a lateral extension arm i^4 , both of which are rigidly attached to the die tube I. The inner end i^x , of the die tube I, constitutes the male die, which, in conjunction with the female die j, severs the left hand reinforcing patch from the strip s' . The female die j, is secured to the right hand side of the bearing i^2 , between which and the inner face of said female die j, is the strip slot a^7 , through 85 which the ribbon s' , passes up to the guide a^8 , on its way to the forwarding rolls d^4 , d^5 , as before stated.

The right hand or outer patch die tube K, and the punch and ejector E, in like manner 90 are mounted in axial alinement with the left die tube I, in and between bearings e, e', forming part of the front bracket e², supported rigidly on front extensions a^{23} , a^{24} , of frame base a. To the left or inner side of 100 the bearing e, is fastened the female die m, which, in conjunction with the male die end k^x , of the tube K, effects the severing of the patch s^{22} , from the portion of the patch strip s^2 , in the strip slot a^{71} , and its transfer to 105 the outer side of the envelop flap f. By reference to Fig. 23, it will be noted that the two male dies i^x , and k^x , act in conjunction to simultaneously press the patches just severed from the strips s' , s^2 , against the envelop flap f, each die acting as an anvil for the other in this respect. The forward or work stroke of the right hand die tube K, is effected by the bifurcated outer end of the cam lever D², which straddles said tube K, 110 between collar nuts k, k' , adjustable upon the threaded portion k^2 , of said tube K, as indicated particularly in Figs. 20, and 21. As before stated the right hand die tube K, is hollow, being formed with the axial bore 115 k^3 , in which the operative end e^x , of the punch ejector E, is slidably supported. The punch E, e^x , is actuated by the cam lever D², the forward bifurcated end of which straddles the threaded shank e^{21} , of the ejector E, 120 e^x , between the collar nuts e^8 , e^4 , adjustable thereon for the purpose of compensating for wear etc.

The working thrust of the punch e^x , is 125 timed to take effect when the two patches 130

s'' , s^{22} , have been pressed forcibly against opposite sides of the envelop flap f , and are held there by and between the opposed faces of the male dies i^* , k^* , as shown in Fig. 23.

- 5 Under these conditions the working thrust of the punch e^* , (the hollow end of the male die i^* , in this case acting as a female die for the time being) punches all three thicknesses of paper, *i. e.*, the patch s^{22} , the envelop flap 10 f , and the patch s'' , the severed material from each being, as a wad, forced into the longitudinal axial channel i^* , (as indicated in Fig. 28) from the outer end of which it is finally ejected by the accumulation of wads 15 from succeeding operations of the punch e^* , which thus obviously also performs the function of an ejector. The discharge channel i^* , is made one thirty second of an inch larger in diameter than the cross section of 20 the punch e^* , to afford clearance for the wads.

Rigidly secured to the right hand die tube K, is the block N, upon which the print plunger N' is rigidly mounted, said plunger 25 extending below the die tube K, and parallel therewith. The distance between the axes of the die K, and of the plunger N', is equal to that of the intermittent feed of the patch strips, so that the center of the imprint n' , made by the type die n^2 , will coincide with that of the next patch s^{22} , to be severed from the patch strip s^2 . Hence it 30 will be seen that at each working stroke or thrust of the right hand die tube K, and 35 ejector punch E, a patch s^{22} , will not only be severed and applied to the outer side of the envelop flap f , but that the imprint n' , for the next succeeding outside patch s^{22} , will also be made. This is illustrated in Fig. 34, 40 in which a portion of the patch strip s^2 , is shown with the holes s^{23} , made by the removal of preceding patches, the patch s^{22} , just severed being shown as still in relative position, while the imprint n' , made by the 45 type die n^2 , for the next succeeding patch is shown below. The finished and applied patch s^{22} , is also shown in Fig. 27.

The letters or characters n' , to be imprinted on the outer patch s^{22} , are preferably made on an intaglio die n^2 , formed 50 with a shank fitting into a mortise formed for its reception in the end of the plunger N', or otherwise constructed to be detachably connected, so that different dies n^2 , may be 55 substituted for different runs of work according to requirements.

The inking for the imprint is done by means of a ribbon q , similar to those used in type writing machines, and fed intermittently in an analogous manner. Thus the ribbon q , passes from the supply spool q' , (Fig. 20) mounted on top of the bracket arm a^{22} , through the horizontal slot or recess e'' , in the bearing e , and in front of the print die n^2 , (see particularly Fig. 24) to the take

up spindle q^2 , mounted upon a pin e^3 , on a forward extension e^4 , of the bracket e^2 , upon which the outer patch die tube K, and ejector punch E, are mounted. The spindle q^2 , is provided with a ratchet wheel 70 q^3 , which is actuated by a flexible spring pawl d^* , upon the front end of the cam lever D^2 , so that during the retractile thrust of the latter the spindle q^2 , is partially rotated to advance the ink ribbon q , prior to the next 75 advance of the printing plunger N',—the spring detent q^4 , counteracting retractile strain and holding the ribbon q , taut. When it is desired to wind the ink ribbon q , back upon the spool q' , the spring detent q^4 , is held from contact with ratchet q^3 , and the spool q' , is re-wound by means of a handle or equivalent q'' .

The lower part of the plate m' , in which the female die m , is mounted performs the function of a bed or platen against which the imprint die n^2 , acts, but, owing to the fact that the gummed side of the patch strip s^2 , is opposed thereto, I prefer to interpose between the plate m' , and the said die n^2 , an "anti-friction" platen plate m^2 , shown in perspective in Fig. 26, and in horizontal section in Fig. 24. The distinctive feature of this platen plate m^2 , is that it is formed with a relief anvil surface m^3 , (annular in the present case) to oppose the impact of the die n^2 , with the least possible contact with the gummed inner surface of the patch strip s^2 ,—the clearance spaces in and around said relief anvil surface m^3 , reducing contact with the strip s^2 , to the minimum, and thereby preventing undue and unnecessary strain on the strip in forwarding it by tension through the machine as hereinbefore described. The plate m^2 , may be secured in place by a thumb screw m^4 , or other mechanical expedient; and is readily removable for cleaning, substitution to compensate for wear, change in shape of imprint die n^2 , or other reason. This platen plate m^2 , is preferably made of brass on account of its well known non-adhesive quality, and also because of its immunity to chemical attack by the ingredients in the adhesive used.

The support for the anvil o , for the clip "riveting" or eyelet punch n^* , is formed by a forward extension of the die plate j' , which is secured to the outer side of the bearing block z^2 , forming part of the bracket i , on which the die tube I, is mounted. The means of securing the pronged and eyeleted clip t , shown in Fig. 31, to the envelop body f' , will be understood most readily by referring to Fig. 29, which shows the relative positions of parts prior to the riveting action, and to Fig. 30, which illustrates the latter.

The eyelet riveting punch R, considered as a whole, is rigidly mounted on the extension arm i^* , heretofore described as rigidly at- 130

tached to the die tube I. Its operative end or shank r , is further centralized and supported by passing through a bearing plate u' , secured rigidly to the back of the lower 5 extremity of the channel standard U, which at this point is formed with a recess u^4 , extending through it into which the shank r , of the punch R, protrudes when advanced as shown in Fig. 30. The punch proper, r^x , is 10 tubular, and preferably formed by inserting a tube r^x , in the drilled end of the shank r , as shown in detail in Fig. 49,—an axial recess r^y , of less diameter than the punch tube r^x , being also drilled in the shank r , for the 15 compressible spring r^2 , which bears upon the head r^3 , of the centralizing pin r^4 . The diameters of the bore of the punch tube r^x , and of the centralizing pin r^4 , which fits it are less than that of the spring recess r^y , so that 20 the inner end of the punch tube r^x , forms a shoulder against which the head r^3 , of the centralizing pin r^4 , is held normally by the spring r^2 , said head being of nearly the same diameter as that of the spring recess 25 r^y . The function of the centralizing pin r^4 , is to support, forward and present the lowest clip t , in the feed channel u , to the upsetting die o' , of the anvil o , during the work thrust of the punch R. This it does by entering the eyelet of the clip t , and supporting the latter until the end of the centralizing pin r^4 , contacts with the upsetting die o' , when the continued advance of the punch R, causes the compression spring r^2 , to yield 30 to said pin r^4 , and allow the end of the punch tube r^x , to push the eyelet of the clip through the portion f' , of the body of the envelop and against the upsetting die o' , as illustrated in Fig. 30, and with the result shown 35 40 in Fig. 32, in a manner well known in the art.

The punch R, may itself be made laterally adjustable and horizontally adjustable upon its supporting arm i^4 , by resort to any desired or well known mechanical expedient, 45 so that I do not limit myself in this respect, the main object being to furnish means whereby both punch R, and feed channel standard U, may be adjusted alike in position as related to each other and as related 50 to the relatively fixed axial positions of the dies and punch I, K, and E. As shown in the drawings by way of illustration, referring particularly to Figs. 29, 30, and 50, the punch R, is mounted in a split box z , positioned in a longitudinal rectangular slot i^4 , formed for it in said supporting arm i^4 , which is also provided with binding screws z' , z'' , arranged to contact with the upper half of the box z , at any position to which the box 55 60 may be adjusted in said longitudinal slot i^4 . The binding screws z' , z'' , are designed to secure the punch R, rigidly to the supporting arm i^4 . i^6 , is a collar upon the punch R, which facilitates the positioning of the

punch accurately upon the arm i^4 , as related 65 to the channel standard U.

The fastening clips t , are fed to the rivet punch R, through the channel u , into the upper end of which they are fed by the rotatable conical portion of the hopper V, 70 mounted upon a shaft V' , which is journaled in a bearing u' , supported upon the upper end of the channel standard U, and in a bearing v , on the upper end of the standard V^2 . The bearing v , is made adjustable horizontally, toward or from the front 75 of the machine, upon the top of its standard V^2 , by any suitable means, as by slots v' , v'' , and screw bolts v^2 , v^3 , as shown in Figs. 16, and 19; and the channel standard U, is 80 made correspondingly adjustable by being mounted near its lower extremity upon a foot piece U' , formed with an elongated slot u^2 , through which a bolt u^3 , passes to secure the foot piece U' , and standard U, 85 adjustably to the upper side of the bearing i^2 , on the bracket i . The positions of the foot piece U' , and channel standard U, are indicated in dotted lines in Fig. 20, and the foot piece U' , in section in Fig. 21. 90

The object of provision for the horizontal adjustment of the eyelet-riveting punch R, and the channel standard U, and bearing v , on the standard V^2 , is to provide for the changing of these parts with relation to the 95 patch dies I, K, and E, to compensate for variations in length of the envelop flaps to the bodies of which the clip fastenings are to be applied.

The bearing u' , for the inner end of the 100 feed shaft V' , is formed in a plate V^3 , attached to the upper end of the channel standard U, said plate V^3 , being formed with a flat vertical surface v^3 , facing the inner side of the rotatable portion V, of 105 the feed hopper, and with the receiving hopper v^4 , into and through which the clips are dumped into said rotatable hopper V, as will be understood by reference more particularly to Fig. 5.

This figure, as well as Fig. 13, show the manner in which the rotatable portion V, of the hopper is yieldably mounted on the inner end of the shaft V' . That is to say 110 said portion V is not secured to its shaft V' , to rotate positively therewith under all conditions, so that, in the event of a clog or jam in the feed between the face plate V^3 , and said rotatable portion V, of the hopper the latter will cease to rotate with 115 its shaft V' , thereby obviating damage. This result is attained by mounting the hub v^5 , of the rotatable portion V, on a portion v^6 , of the shaft V' , formed with a shoulder v^7 , against which the hub v^5 , is pressed normally by a spring v^8 , held in position on the threaded end v^9 , of the shaft V' , by a thumb nut v^{10} , so as to be compressible more 120 125

or less tightly against the outer face of the said rotatable conical section V, of the hopper. Hence, obviously, said section V, is held to rotate with its shaft V', only by the 5 frictional resistance afforded by the elastic resilient pressure of said spring v⁸, so that when the resistance to rotation with the shaft V', encountered by the conical part V, is greater than the frictional resistance exerted by the spring v⁸, the otherwise rotatable conical part V, will be held stationary with the face plate V³, and consequently the portion v⁶ of the shaft V', will simply slip around within the hub v⁵, of said conical 10 part V. Under such conditions it is needless to say that the conical section V, may be readily loosened upon the shaft V', or possibly removed, so that the cause of obstruction may be quickly ascertained and 15 remedied without danger of injury to any part of the apparatus, and without delay or serious loss of time.

The feed shaft V', is held against longitudinal movement by its shoulder v⁹, resting against one side of the bearing u', and by a collar v¹², secured to the shaft V', and resting against the other side of said bearing u', as shown in Figs. 5, and 13. A fixed pulley v¹³, on the shaft V', affords means 20 whereby the conical section V, of the hopper may be continuously rotated at a moderate speed.

While I have thus provided as above set forth for any unforeseen obstruction to the 25 operation of the feed hopper I reduce danger thereof to the minimum degree by my means for, and method of, feeding the eyelet clips to the delivery channel u.

By reference to Fig. 12, it will be seen 30 that the inner edge of the conical section V, of the feed hopper is formed with a series of equi-distant tangential slots v¹⁴, the open sides of which are opposed to the flat vertical surface v³, of the face plate V³. The shoulder v⁷, on the shaft V', holds the 35 rotatable section V, so that its slotted edge is positioned, say, one sixteenth of an inch (less than the depth of the eyelets but greater than the thickness of the prongs) 40 from said opposed surface v³, of the face plate V³, thus creating an annular space v¹⁵, between them sufficient to accommodate the prongs of the clips t, but not sufficient to admit the eyelets of the clips, which however are free to enter the tangential slots 45 v¹⁴. As a result of this construction the rotation of the conical section V, causes some of the clips to enter the space v¹⁵, with their eyelets projecting into the tangential slots v¹⁴, and to be carried around to the mouth u⁵, of the channel u, said mouth v⁵, being formed in the face of the plate V³, as indicated in dotted lines in Fig. 12, and shown in solid lines in Fig. 14, by

reference to which latter, and to Fig. 13, 65 it will be seen that the mouth u⁵, of the channel is also formed with overlapping edges u⁸, u⁶, which are continuations of those on the channel u, shown in cross section in Fig. 6.

The clips thus forwarded in the direction of the arrow, Fig. 12, drop into the mouth u⁵, of the channel u, if there is room therein, otherwise they are carried over, controlled by the overlapping edge u⁶¹, (see Fig. 75 14) to the deflector v¹⁰, by which they are shunted back into the mouth v⁴, of the hopper to be returned thereby to the rotatable section V.

The eyelets are supported in the channel u, 8 until required for use, by the check or escapement lever u⁷, which is of the rock lever class, pivotally supported at u⁸, on the channel standard U, and is formed with points u⁹, u¹⁰, which contact alternately with the 85 eyelets of the clips as they are checked off to the lower part of the channel. When at rest in normal position as shown in Fig. 9, the upper arm u⁷, of the escapement lever u⁷, rests against the side of the channel 90 standard U, while when rocked over into the position shown in Fig. 52, its lower arm u¹², bears against said channel standard U. The point u⁹, sustains the column of clips in the channel u, above as in Fig. 9, until rocked 95 back into the position shown in Fig. 52, when the point u¹⁰, sustains the column of slips temporarily until returned to normal position as in Fig. 9, such return allowing the lowest clip to drop to its seat below, 100 while the point u⁹, intercepts the next succeeding clip and thereby again sustains the column of clips above.

The released clip descends from the escapement to a seat u¹³, at the bottom of the 105 channel u. This seat u¹³, may be formed directly in the channel standard U, or may be formed in a separate piece u¹⁴, to be attached rigidly thereto, as may be found most expedient. The seat u¹³, positions the clip 110 with its eyelet in alignment with the centralizing pin v⁴, of the eyelet-riveting punch R. The eyelet is held in position on the seat u¹³, by the front edges of the gates u¹⁵, which overlap the eyelet flange and prevent the clip from displacement until forwarded by the riveting punch R, as hereinbefore fully set forth, under the action of which punch the gates yield, being closed normally by springs u¹⁶, u¹⁷,—said gates u¹⁵, u¹⁶, being of course pivotally attached to the lower end of the channel standard U, as at u¹⁷, u¹⁷. The gates u¹⁵, u¹⁶, are also provided with rear projections or handles u¹⁸, u¹⁸, by which they may be manually manipulated when 120 access is desired to the seat u¹³, to remove a defective clip, or to empty the channel for any reason,—the escapement lever u⁷, being

also in like manner preferably provided with a handle or projection u^{11} , by which it may be manually manipulated for the latter purpose.

5 To provide for this manual manipulation of the escapement u^7 , when desired, and also to obviate possibility of damage by the use of rigid positive means of operation, I connect said escapement lever u^7 , with the cam lever D^4 , by means of a coiled spring u^{10} , attached to an extension d^{62} , on said cam lever D^4 , and to the upper arm u'' , of the escapement lever u^7 , as indicated in Fig. 40. Thus when the cam lever D^4 , is in its raised normal position as shown in solid lines in said figure the spring u^{10} , holds the escapement lever u^7 , with its upper arm u'' , against the channel standard U , as in Fig. 9, and when it is lowered as in dotted lines in Fig. 40, it 10 depresses the said escapement lever u^7 , into the position shown in Fig. 52, with its arm u^{12} , in contact with the channel standard. This 15 elastic resilient connection between the escapement and its actuating cam lever is 20 amply sufficient to operate the escapement without danger to the delicate clips, while admitting also of the manipulation of the escapement by hand when desirable, as is 25 frequently the case in the operation of the 30 machine on account of the presence of defective clips in the channel u .

In this connection it may be stated that the channel standard U , is so positioned with relation to the operator, that the clips 35 in the channel u , are always exposed conveniently within the line of vision of said operator so that defective clips may be removed, or other precautions taken to prevent damage or delay. This is an important 40 practical advantage in the operation of the machine in order to attain the best results therewith.

The envelop feed or work table W , upon which the envelop F , is positioned for subjection to the several simultaneous operations hereinbefore set forth, is supported upon a nut block w , adjustably mounted upon a vertical screw X , journaled in a pendent bracket X' , the upper end of which 45 is attached to the under side of the base or table a . The bracket X' , is formed with the two rear extensions x^1 , x^2 , in and between which the adjusting screw X , is journaled, said screw being provided with a stress 50 collar x , bearing against the upper side of the lower extension x^2 , and with a crank x^3 , on its lower extremity beneath the said extension x^2 , as will be seen more particularly by reference to Fig. 35. The vertical member x^4 , of the bracket X' , is formed with a longitudinal slot x^5 , (shown in Fig. 21) through which a forward extension x^6 , of the nut block w , protrudes, and on this extension w' , the bifurcated lower end of 55 the leg w^2 , of the work table W , is pivotally 60

supported, as at w^3 . The inclination of the work table W , is regulated and prescribed by a screw Y , the head y , of which rests against and supports the leg w^2 , while its upper end engages with a female screw 70 thread formed for its reception in the nut plate w^4 , secured to the top of the nut block w . It is obvious that this adjustment of inclination of the work table W , may be effected by the use of other mechanical expedients with like result,—the object of the adjustment being to compensate for any variation or irregularity in shape of a run of envelopes, so as to always have the clip fastening t , on the envelop body f' , in operative alinement with the reinforced hole s , in the flap f . If the envelop is perfectly rectangular in shape the work table W , should be horizontal as shown in solid lines in Figs. 21, and 35, but it frequently happens that a whole batch or run of envelopes 80 will be found to be uniformly distorted either through carelessness, imperfection of cutting dies, folding, or the like, in which case the operator of my machine can, by 85 means of the screw Y , quickly and conveniently counteract the defect. In Fig. 35, in which the work table is shown in dotted lines as inclined, for convenience of illustration the degree of inclination is much exaggerated, but in actual practice the degree of 90 inclination called for under ordinary conditions is comparatively slight. Of course the inclination may be set above or below the horizontal according to circumstances, but 100 in any case is to bring the clip eyelet in the body of the envelop into correct central longitudinal alinement with the prong opening in the flap thereof.

The length of the supporting screw X 105 on which the work table W , is vertically adjustable, is sufficient to cover variations in width of envelopes from one to fourteen inches.

The position of the envelop on the work 110 table W , is prescribed by a gage w^5 , attached to the upright flange of a plate w^6 , which is adjustably secured to the top of the table W , by thumb nuts w^7 ; engaging screws w^8 , on the table which project up through 115 longitudinal slots w^9 , in the gage plate w^6 , as shown in Fig. 36, or by resort to any other preferred mechanical expedient. The gage w^5 , is formed with an inturned projection or finger w^{10} , which protrudes into the 120 interior of the envelop, the edge of the body portion or mouth of the envelop resting, when the envelop is properly positioned, in the bight or angle of the gage w^5 , as indicated in Fig. 35. In this position the flap 125 f , of the envelop projects in between the die plates m , and j , the latter protruding into the open mouth of the envelop so that its forward portion may be utilized as an 130 anvil support for the eyelet riveting mecha-

nism as hereinbefore set forth, while the proper portion of the flap is interposed between the hole-perforating and reinforcing mechanism, and exposed to the action of the 5 imprint die.

In this connection it may be stated that while described herein as imposed on the outer reinforcement patch the imprint may be made on any other part of the envelop 10 flap if preferred.

Furthermore, while I have herein shown and described the use of annular reinforcing patches, dies, etc., it is obvious that other forms of patches may be provided for in 15 like manner, and that various modifications and mechanical expedients may be resorted to without departing from the spirit and intent of my invention in this respect.

The operative use of the apparatus is as 20 follows:

The eyelet riveting punch mechanism having been adjusted to a position in front of the hole punching and patching mechanism at which the axial distance between the two 25 mechanisms is equal to the proper requisite distance between the eyelet clip applied to the body of the envelop and the reinforced prong hole formed for the reception of its 30 prongs on the flap thereof, and the work table W, in a horizontal position, having been vertically adjusted to accommodate the width of the envelop, a trial envelop is positioned on the work table and the gage thereon set to limit and prescribe the distance the flap is to protrude between and beyond the patch dies and hole punch. The treadle is then depressed to release the clutch sleeve on the cam shaft, allowing it to engage with the power pulley to rotate the cam 35 shaft. The treadle being immediately released, the cam shaft will make one revolution and then again come to rest for reasons hereinbefore set forth. During this revolution of the cam shaft a cycle of actions by 40 the several mechanisms take place; *i. e.*, the patch dies remove a circular patch from each patch strip and press them against opposite sides of the envelop flap, and the imprint die acts on the ink ribbon to make the imprint 45 for the next envelop, when the perforating die immediately thereafter punches the central prong opening through both patches and the envelop flap, forcing the severed wad into the discharge passage in the left 50 hand patch die tube. Simultaneously the eyelet riveting punch has advanced, taken up the eyelet clip at the bottom of the feed channel, and forced its eyelet through the opposed portion of the envelop body and 55 against the upsetting die, which turns over and clenches the edges of the eyelet. After the punching of the prong hole in the flap and patches as above stated the patch and print dies and the hole punch retire, when 60 the forwarding cam raises its lever and with

it the pawl which rotates the ratchet connected with the strip feed rolls thereby drawing the patch strips into position for the next reciprocation of the patch dies and punch. As the forwarding cam lever is allowed to resume its normal position during the completion of rotation of the said cam, said lever by its connection with the escapement lever on the clip feed channel rocks said escapement so as to check off and 70 release the next succeeding clip in the channel and allow it to descend into position for the next operative stroke of the eyelet-riveting punch. During the retractile movement of the cam lever which actuates the right 75 hand patch die and the imprint die, the spring pawl carried upon the outer end of said lever actuates the ratchet on the ink ribbon spindle to forward said ink ribbon to present a fresh surface for the next advance 80 stroke of said imprint die.

The machine being now again at rest at the completion of this single revolution of the cam shaft, since the clutch sleeve has automatically detached itself from the 85 power pulley, and the detent lever has again engaged with its notch or depression in the strip forwarding cam (or in fact as soon as the retractile stroke of the dies and punches has begun) the envelop may be removed and 90 examined. If found to be of imperfect rectangular shape, which will be indicated by lack of perfect alinement between the clip fastening on the envelop body and the prong opening in the flap thereof, the feed 95 table is adjusted in inclination to compensate for such defect, and if the indications are that the defect extends through a run or batch of envelops such adjustment may be maintained for the time being. After the 100 proper adjustment of the feed table is thus ascertained the feed to, and operation of, the apparatus may be conducted continuously, though intermittently, in that the treadle may be depressed practically as fast 105 as a completed envelop can be withdrawn and another substituted. And when it is considered that there are essentially four operations performed on each envelop treated, to wit, the application of the 110 patches, the punching of the prong hole and the imprint on the flap, and the application of the eyelet clip fastening to the body thereof, it is obvious that a very important saving is effected in both time and labor of 115 manipulation, one handling of the envelop answering for all.

Incidentally it may be noted that by my special clip eyelet riveting means the eyelet is made to penetrate through the envelop 120 body without previous or preparatory puncture thereof, a saving of what has heretofore constituted a separate operation.

What I claim as my invention and desire to secure by Letters Patent is,

1. In apparatus of the character designated, in combination, means for forming and reinforcing a clip-prong hole in the flap of an envelop, an imprint die movable with and arranged to act in conjunction with said hole forming and reinforcing means, and means for positioning an ink ribbon in front of said imprint die, for the purpose described.
- 10 2. In apparatus of the character designated, in combination, means for forming and reinforcing a clip-prong hole in the flap of an envelop, an imprint die movable with and arranged to act in conjunction with said hole forming and reinforcing means, and means for feeding an ink ribbon in front of said imprint die.
- 15 3. In apparatus of the character designated, in combination, means for forming and reinforcing a clip prong hole in the flap of an envelop, an imprint die movable with and arranged to act in conjunction with said hole forming and reinforcing means, and means for automatically feeding an ink ribbon in front of said imprint die, for the purpose described.
- 20 4. In apparatus of the character designated, in combination, a reciprocatory die and a punch for forming and reinforcing a clip hole in an envelop flap, an imprint die rigidly secured to move with said first mentioned die and punch, means for reciprocating said dies and means for feeding an ink ribbon in front of said imprint die, said ink ribbon feed means being actuated by the means for reciprocating the dies.
- 25 5. In apparatus of the character designated, in combination, opposed reciprocatory dies and a punch for forming and reinforcing a clip hole in an envelop flap, an imprint die rigidly secured to reciprocate with one of said hole reinforcing dies, means for reciprocating the dies thus united to work in unison, and means for feeding an ink ribbon in front of said imprint die, said ink ribbon feed means being actuated by the means for reciprocating the dies.
- 30 6. In apparatus of the character designated, in combination, opposed reciprocatory dies and a punch for forming and reinforcing a clip hole in an envelop flap, an imprint die rigidly secured to reciprocate with one of said hole reinforcing dies, means for reciprocating the dies thus united to work in unison, and means for feeding an ink ribbon in front of said imprint die, said means consisting of an ink ribbon spool and an ink ribbon winding spindle provided with a ratchet wheel and detent and actuated by a spring pawl upon the means for reciprocating the dies.
- 35 7. In apparatus of the character designated, in combination, mechanism for forming a clip prong hole in and on the flap of an envelop and reinforcing the same by means of patches stamped from patch strips, and an imprint die movable with and acting in unison and conjunction with said hole forming and reinforcing mechanism and arranged to impose an imprint on a patch strip in such position thereon as to be included on the next succeeding patch to be severed and applied to the envelop flap.
- 40 8. In apparatus of the character designated, in combination, means for forming a clip prong hole in the flap of an envelop and for reinforcing said hole by means of patches detached from strips of suitable material, and means movable with and acting in conjunction with said hole forming and reinforcing mechanism for simultaneously imposing an imprint on one patch strip, for the purpose set forth.
- 45 9. In apparatus of the character designated, the combination of a reciprocatory imprint die, opposed reciprocatory means for forming and reinforcing a clip hole in an envelop, said imprint die being mounted for movement with one of said first-named dies, and means for feeding an ink ribbon in front of the imprint die.
- 50 10. In apparatus of the character designated, in combination, mechanism for forming and reinforcing a prong hole in an envelop flap consisting of opposed patch and punch dies, of a block rigidly attached to one of the dies, a plunger mounted thereon in parallelism to the die to which the block is secured, a printing die carried by said plunger, a platen opposed thereto, and means for passing a patch strip between said printing die and said platen.
- 55 11. In apparatus of the character designated, the combination with means for forming and reinforcing a clip-prong hole, and for simultaneously making an imprint in connection therewith, the imprint means being movable with said forming and reinforcing means, of patch strip forwarding rolls, and scrapers arranged to remove gum, fiber, etc., from the peripheries of said rolls.
- 60 12. In apparatus of the character designated, the combination with means for simultaneously forming and reinforcing a clip-prong hole, making an imprint in connection therewith, and applying a prong clip, the imprint means being movable with said forming and reinforcing means, of a work table provided with an adjustable gage formed with an inturned and upturned gage finger adapted to enter the mouth of an envelop, for the purpose described.
- 65 13. In a machine for attaching flap locking means and reinforcing material to envelops and the like, the combination of means for holding a strip of reinforcing material, means for intermittently advancing the strip to a predetermined extent, means for guiding a strip, strip printing means, strip punching means adapted to punch out the

printed portion of said strip, said printing means being movable with and adapted to act in conjunction with said punching means, and means coöperating with said strip 5 punching means to press the printed and punched out portion into effective adhering contact with an envelop or the like.

14. In a machine for attaching flap locking means and reinforcing material to envelops and the like, the combination of 10 means for holding a gummed strip of reinforcing material, means for moistening said strip, strip feeding means including coöperating rollers adapted to engage said strip therebetween, and a ratchet and pawl to actuate said rollers intermittently, means for printing on the strip, including a die mounted on a plunger, an ink carrying ribbon disposed in the path of said die, strip guiding means adapted to position the strip to receive an impression from said die and ribbon, and means for feeding the ribbon intermittently, means for punching out a previously printed portion of said strip, said 25 printing die being movable with and adapted to act in conjunction with said punching means; and means for pressing the punched

out portion into adhering contact with an envelop or the like.

15. In apparatus of the character designated, the combination with means for simultaneously forming and reinforcing a clip-prong pole, making an imprint in connection therewith and applying a prong clip, the imprint means being movable with said forming and reinforcing means, of a work table which is adjustable in inclination for the purpose set forth. 30

16. In apparatus of the character designated, the combination with means for simultaneously forming and reinforcing a clip-prong hole, making an imprint in connection therewith and applying a prong clip, the imprint means being movable with said forming and reinforcing means, of a work 35 table which is adjustable vertically with relation thereto, and also adjustable in inclination with relation thereto, for the purpose set forth. 40
